(57) **CLAIM**

The ornamental design for a combined cutter and grater, as shown and described.

DESCRIPTION

FIG. 1 is a top plan view of a combined cutter and grater showing my new design.

FIG. 2 is a front perspective view thereof, the rear perspective view is a mirror image.

FIG. 3 is a right side perspective view thereof.

FIG. 4 is a right, bottom perspective view thereof.

FIG. 5 is a left side elevation view thereof.

FIG. 6 is a bottom plan view thereof.

FIG. 7 is a right side elevation view thereof.

FIG. 8 is a right side perspective view thereof with the cover shown in an open position.

FIG. 9 is a bottom, right perspective view of FIG. 8 with the cover shown in a closed position.

FIG. 10 is a bottom plan view of FIG. 9.

FIG. 11 is a right side perspective view of FIG. 1 shown attached to a round bowl.

FIG. 12 is a right, rear perspective view of FIG. 11.

FIG. 13 is a right side perspective view of FIG. 1 shown attached to a round bowl.

FIG. 14 is a right, rear perspective view of FIG. 13.

FIG. 15 is a right side perspective view of FIG. 1 with the cover removed.

FIG. 16 is a top plan view of FIG. 15.

FIG. 17 is a right side perspective view of FIG. 15.

FIG. 18 is a front perspective view of FIG. 15.

FIG. 19 is a right, front perspective view of FIG. 15 shown attached to a round bowl; and,

FIG. 20 is a front perspective view of FIG. 19.

The broken lines showing various cutters and graters and bowls are for illustrative purposes only and form no part of the claimed design.

1 Claim, 20 Drawing Sheets
